DRY CLEANING COMPOSITIONS

Arthur Andrew Levine, Niagara Falls, N. Y., assignor, by mesne assignments, to E. I. du Pont de Nemours and Company, a corporation of Delaware

No Drawing. Application September 18, 1931,
Serial No. 563,671

2 Claims. (Cl. 87—5)

This invention relates to the art of soap making and more particularly to the manufacture of soap for use in dry cleaning with chlorinated hydrocarbon solvents.

Soaps for use in dry cleaning must have the ability to dissolve in the dry cleaning fluids and yet not hydrolyze or precipitate therefrom in the presence of small amounts of water. Various dry cleaning soap preparations have been proposed which contain so-called "stabilizers" which to a greater or lesser extent inhibit precipitation or deterioration in the presence of water. These preparations have not been satisfactory for use with chlorinated hydrocarbon dry cleaning solvents because their solubility in such solvents is limited. A further disadvantage is that the "stabilizer" has often a low boiling point and when the solvent is purified by distillation, the stabilizer is not separated therefrom. When the solvent has been reused and repurified a number of times, the quantity of stabilizer thus introduced is often sufficient to appreciably alter the properties of the solvent.

An object of this invention is to provide a dry cleaning soap preparation which is miscible in substantially all proportions in chlorinated hydrocarbon dry cleaning solvents and which is stable in the presence of relatively large amounts of water. A further object is to provide a soap which does not contain relatively low boiling constituents. A still further object is to provide a soap which exerts no solvent action upon dyes or fabrics. Other objects will appear hereinafter.

These objects are accomplished by incorporating one or more of the polyglycols in a fatty acid soap, with or without the addition of a chlorinated hydrocarbon.

According to one method of practicing my invention, I saponify a fatty acid with a caustic solution and add a chlorinated hydrocarbon, for instance trichlorethylene, and a polyglycol, for instance diethylene glycol or triethylene glycol. The soap so obtained has excellent detergent properties and is soluble in all proportions in chlorinated hydrocarbon dry cleaning solvents.

The following examples serve to show some methods of practicing my invention.

Example 1

14.2 g. of NaOH was dissolved in 25 cc. of water and the resulting caustic solution was added with vigorous stirring to a mixture of 100 g. of oleic acid and 100 cc. of trichlorethylene. To the resultant paste, 70 g. of triethylene glycol was added, forming a perfectly clear solution. This

soap was completely soluble in trichlorethylene and had excellent detergent properties. There was no sign of precipitation when up to 5 cc. of water was added to 100 cc. of the liquid soap.

Example 2

14.2 g. of NaOH was dissolved in 25 cc. of water and added drop by drop to a mixture of 100 g. of oleic acid and 100 cc. of trichlorethylene. To the resulting paste, 50 cc. of diethylene glycol was added, giving a perfectly clear solution, soluble in trichlorethylene in all dilutions.

Example 3

14.2 g. of NaOH were dissolved in 25 cc. of water and added drop by drop to a mixture of 100 g. oleic acid and 100 cc. of carbon tetrachloride. To the resulting paste, 70 cc. of triethylene glycol was added, giving a perfectly clear solution of this soap, soluble in carbon tetrachloride in all dilutions.

Although the examples cited show soaps prepared by saponification of a fatty acid in the presence of chlorinated hydrocarbon, I may prepare soap by any of the well known methods and then dissolve this soap in chlorinated hydrocarbon and polyglycol or mix it with polyglycol alone.

Although I prefer to add sufficient chlorinated hydrocarbon to the soap to form a solution, my invention is not limited to the preparation of a liquid soap but may include other forms such as jellies and pastes. For instance I may prepare a paste by mixing soap with polyglycol alone. Such paste is completely soluble in chlorinated hydrocarbon dry cleaning solvents, for instance trichlorethylene or carbon tetrachloride.

In dry cleaning with my soap preparation, it is preferable to use a soap containing as one constituent the same solvent that is used as dry cleaning agent; but this is not essential. For instance, a soap made according to my invention and containing trichlorethylene may be used in dry cleaning operations employing either trichlorethylene or carbon tetrachloride as solvent.

Relatively large quantities of water may be added to solutions of my polyglycol soaps in dry cleaning solvents without causing precipitation. For instance I found that no sign of precipitation or cloudiness occurred when 4.5 cubic centimeters of water were added to 1 liter of a 1% trichlorethylene solution of a soap made as herein described and containing diethylene glycol. This toleration of relatively large amounts of water makes possible excellent dry cleaning without the

special precautions to exclude moisture heretofore necessary in cleaning with mixtures of chlorinated hydrocarbon solvents and soaps.

- 5 In the distillation of a solvent which has been used in a dry cleaning operation, it is desirable that the distilled solvent be not contaminated by material derived from the dry cleaning soap. Although the amount of such material introduced may be relatively small during each operation, 10 after repeated dry cleaning and distillation operations the amount becomes significant. The solvent properties of the dry cleaning solvent likewise become altered after several recoveries when soap having volatile constituents is used. When 15 polyglycols are used as stabilizers in dry cleaning soaps, substantially no such contamination of the dry cleaning solvent results, because the high boiling points of these stabilizers prevent them from distilling with the solvent.
- 20 The polyglycols have substantially no solvent action on cellulose acetate under the conditions normally existing in dry cleaning processes; and soaps made according to my invention may be used for dry cleaning cellulose acetate fabrics 25 without danger of harming the goods.

The advantages of my soap may be summarized as follows:

1. Complete solubility in chlorinated hydrocarbon solvents.
- 20 2. May be made either as a jelly or as a liquid.
3. Relatively inexpensive.
4. The boiling point of the stabilizer is high,

which prevents it being distilled over with dry cleaning solvent.

- 5 5. A relatively large amount of water may be present during cleaning operations without causing precipitation or interfering with the detergent action of the soap.

6. Substantially no solvent effect upon dyes or fabrics.

By the term "polyglycol" in the specification and claims, I mean diethylene glycol 10

or the product obtained by the condensation of this material with one or more molecules of ethylene glycol ($\text{CH}_2\text{OH}-\text{CH}_2\text{OH}$). 15

I claim:

1. An odorless dry cleaning composition consisting of trichlorethylene which contains in solution about 1% of a soap composition consisting substantially of 108 parts of an oleic acid—sodium 20 soap, 147 parts of trichlorethylene and 70 parts of triethylene glycol, said proportions being by weight.

2. An odorless dry cleaning composition consisting of trichlorethylene which contains in solution about 1% of a soap composition consisting substantially of 108 parts of an oleic acid—sodium 25 soap, 147 parts of trichlorethylene and 56 parts of diethylene glycol, said proportions being by weight. 30

ARTHUR ANDREW LEVINE.
